Primary Examiner — George D. Kirschbaum

(57) CLAIM

The ornamental design for a sports and fitness equipment, as shown and described.

DESCRIPTION

1. Sports and fitness equipment

1.1 Perspective view

1.2 Exploded view

1.3 back view

1.4 enlarged view

1.5 enlarged view

The article of subject design represents a stylized fencing sword consisting of precast components: a blade with a tip, a grip, a guard and a weight; the mass of the equipment may be changed through weight replacement with another of greater or lesser weight; both blade and its grip are coated with silicone; the tip is also made from silicone; the article is used for training, where the fitness activities and exercises are practiced with such equipment.
